E. G. STAUME.

CARBURETER.

APPLICATION FILED OCT. 10, 1914.

Patented Mar. 18, 1919.

UNITED STATES PATENT OFFICE.

EDWIN G. STAUDE, OF MINNEAPOLIS, MINNESOTA, ASSIGNOR TO E. G. STAUDE MANUFACTURING COMPANY, OF ST. PAUL, MINNESOTA, A CORPORATION OF MINNESOTA.

CARBURETER.

1,297,506.

Specification of Letters Patent. Patented Mar. 18, 1919.

Application filed October 10, 1914. Serial No. 866,152.

To all whom it may concern:

Be it known that I, EDWIN G. STAUDE, a citizen of the United States, residing at Minneapolis, in the county of Hennepin and State of Minnesota, have invented a new and useful Improvement in Carbureters, of which the following, together with the accompanying drawings, is a specification.

The present invention relates to devices for forming the combustible charge for internal combustion engines, and is designed with particular reference to the effective atomization of the liquid fuel, such as gasoline or kerosene, prior to the admixture of the same with the proper portion of air to form such combustible charge.

The devices ordinarily employed for this purpose, depending for their operation upon the suction produced by the down strokes of the engine pistons, are incapable of securing, at all times, a uniform mixture since the variations in the speed of the engine produce varying degrees of suction. Furthermore, in such devices, there is no certainty that the atomization of the liquid fuel will be carried out uniformly, since the conditions controlling the same, such for instance as the temperature and density of the atmosphere, and the specific gravity of the fuel, are subject to wide variation.

The present invention aims to overcome the above mentioned disadvantages common to atomizers and carbureters, by the provision of positive means for insuring the maintenance of an exact proportion between the amount of fuel atomized and the amount of air used in forming the combustible mixture regardless of whether the engine is operating at a high or a low speed. Furthermore, it is proposed to accomplish the atomization for all conditions of operation at a uniform pressure, unaffected by the speed of the engine, thereby insuring a spray of even tension. A further object is to provide such a device adaptable to the atomization of fuels of different specific gravity without requiring any special adjustment. Other and further objects will appear from the following description and the claims annexed thereto, reference being had to the accompanying drawings, in which—

Figure 1 is an end view of the combined carbureter and atomizer embodying my invention.

Fig. 2 is a vertical section on the line 2—2 of Fig. 1, looking in the direction of the arrow.

Fig. 3 is a section on the line 3—3 of Fig. 2, looking in the direction of the arrow.

Fig. 4 is a section on the line 4—4 of Fig. 2, looking in the direction of the arrow.

Fig. 5 is an enlarged detail sectional view of one of the spraying plugs, and

Fig. 6 is a section on the line 6—6 of Fig. 5.

Similar reference characters refer to similar parts in the different figures.

Referring to the drawings, the numeral 1 represents a tubular member containing an air passage, having an elbow 2 supplied with a suitable flange 3 which is adapted to be fastened to the inlet manifold of an internal combustion engine. Within said passage is a suitable butterfly valve 4 of usual construction which is mounted on a shaft 5. A thin boss 6, on the under side of member 1 has secured thereto, by means of screws 7, an annular flange 8 carried at the upper end of an elongated tubular member 9. Said member 9 preferably consists of an upper bearing portion 10, a lower bearing portion 11, and an intermediate open or skeleton connecting portion 12. A shaft 13 having a valve 14 secured to its upper end is disposed in suitable bearings in said portions 10 and 11, and is adapted to be rotated by means of a pulley 15, to which power is applied from any suitable source, preferably the internal combustion engine, not shown, which is supplied with explosive mixture from the carbureter.

The valve 14 is seated within a suitable recess 16 of the member 9, with its upper surface flush with flange 8, and its periphery is formed with a plurality of equidistant pockets 17. Extending radially outward from the recess 16 are a plurality of equidistant passages 18, with the inner ends of which the valve pockets 17 register, as said valve is rotated, as shown in Fig. 4. Said passages 18 open at their outer ends into a common annular fuel chamber 19 connected by a pipe 20 with the fuel supply tank, not shown. Alternating with said passages 18 the upper portion of the member 9 is formed with an annular series of equidistant vertical holes 21, which are connected with the valve recess 16 by

short ports 22. Seated in said holes 21 are the upper ends of vertically movable plunger rods 23, which find bearings at their lower ends in holes 24 formed in the lower bearing portion 11 of member 9. Intermediate their ends said plunger rods have secured thereto collars 25, between the under sides of which and the bearing portion 11 are disposed springs 26 surrounding said rods and serving to yieldingly maintain them at their limit of upward vertical movement.

The shaft 13 has splined thereto, between the bearing portions 10 and 11, a sleeve 27, which is capable of longitudinal movement thereon. A collar 28, loosely carried within an annular recess 29 of said sleeve, so as to permit rotation of said sleeve with respect to the collar by shaft 13, is employed to impart longitudinal movement to the sleeve, said collar having oppositely extending arms 30 apertured to permit the free passage of two of the plunger rods 23 therethrough, as shown in Fig. 3.

The ends of arms 30 are secured to a yoke formed by curved arms 31 carried by a rock shaft 32 which is journaled in lateral projections 33 of the intermediate skeleton portion 12 of the member 9. A lever 34, secured to said rock shaft, carries near its upper end a block 35, which is capable of longitudinal adjustment, lengthwise of said lever, by means of a screw 36 carried by said lever. A pin 37, carried by said block, is disposed within an elongated slot 38 in an arm 39, which is secured to and depends from one end of the shaft 5 of the butterfly valve 4. The other end of shaft 5 carries a suitable throttle lever 40, which is connected with the usual control devices, not shown, for operating the butterfly valve. The construction above described insures the downward movement of the sleeve 27 in direct proportion to the amount of opening movement imparted to the valve 4, as will be readily apparent.

The surface of the sleeve 27 is formed with an inclined cam surface 41, designed for co-operation with the collars 25 on the plunger rods 23. In the rotation of said sleeve, by reason of its splined connection with shaft 13, said cam surface is successively effective, with respect to said collars, to depress said rods in opposition to the force of the springs 26.

In the continuous rotation of the shaft 13, the valve 14 is moved into the position shown in Fig. 4, where the pockets 17 register with the passages 18, permitting the flow of liquid fuel from the pipe 20 to fill said pockets. The further rotation of the valve cuts off the supply to the said pockets and carries said pockets into registration with the ports 22 leading to the cylindrical plunger rod holes 21. Coincident with the rotation of the

valve, the cam surface 41 is operative in depressing the several plunger rods 23, the distance through which the cam surface is operative being dependent upon the position assumed by the sleeve 27 in response to the movement of the butterfly valve, as previously set forth.

During a single rotation of the shaft 13, the rods are successively carried to their limits of downward movement by the cam and, thereafter, the lower end 42 of said cam surface moves out of contact with the collar 25, permitting each rod to move successively upwardly under the influence of its spring 26. The parts are so proportioned and timed that the cam moves out of engagement with the collar 25 of each plunger rod just after the maximum space created above said plunger rod has been filled with liquid fuel from the passage thereacross of one of the valve pockets 17. It will be understood, in this connection, that each pocket 17, immediately preceding its movement in registration with the ports 22, has had its fuel supply replenished to the maximum capacity by registration with one of the passages 18.

Immediately above the open upper end of each plunger rod hole 21, the tubular member 1 carries a sprayer 43, preferably consisting of a hollow plug 44, having a restricted opening 45 at its upper end, as shown in Fig. 5. A bullet shaped plug 46, having longitudinal surface grooves 47 is screw-threaded within the interior of plug 44, its upper end being spaced slightly from the opening 45 to allow for the convergence of the grooves 47 at or near this point.

The upward movement of each plunger rod 23, under the influence of its spring 26, forcibly projects the superposed liquid fuel in the upper end of its hole 21, through the several grooves 47 of the associated sprayer 43, causing the violent impingement of a plurality of sprays at a common center adjacent the restricted opening 45. The fuel charge is thereby broken up into a fine mist or vapor as it passes into the air passage 1, thus facilitating the carburation of the air in said passage. To permit access to the sprayers 43, a removable section 48 is provided in the air passage.

The operation of the device is clear from Fig. 2, where, the butterfly valve 4 being closed, the sleeve 27 is at the upward limit of its movement; it follows, therefore, that the cam 41 is not in a position to operate upon the plunger rods 23. However, when the sleeve 27 is lowered, by the opening of valve 4, the collars 25 on rods 23 are brought under the influence of cam 41, to a greater or less extent, as determined by the amount which the sleeve 27 is lowered. The rotation of the cam 41 gradually retracts the plunger rods, successively, by forcing down

the collars 25, until each collar, successively drops off the end 42 of said cam, and thereupon returns sharply, under the action of its spring 26, to the position shown in Fig. 5 2, thus accomplishing the injection of the liquid fuel as above described.

It is to be noted that the transfer of the liquid fuel into the holes 21 by the pockets 10 17 of the valve is effected when the pressure of the fuel supply, prevailing in the chamber 19 has been cut off, so that there can be no overflow or leakage of fuel into the air passage, to produce too rich a mixture. To prevent the leakage of the liquid 15 fuel, suitable stuffing boxes 49 are provided for each of the rods 23 and for the shaft 13.

The construction herein shown is best adapted to the needs of a four cylinder engine, the parts being so timed as to insure 20 the measuring and injecting action successively for each of the cylinders. By driving the shaft 13 fifty per cent faster, the construction will adapt itself to a six cylinder engine. Or, as will be apparent, the number 25 of plunger rods may be increased or diminished, to conform to the number of engine cylinders.

The injection of the fuel into the sprayers 30 43 is always accomplished under substantially the same pressure, whether the engine be running fast or slow, since such action is merely contingent upon movement of the cam surface 41 out of engagement with the collar 25 of a plunger rod 23. Consequently, 35 the starting of the engine does not require rapid spinning, or a choking down of the air passage.

It is to be noted that the injection of the liquid fuel at a substantially constant pressure, 40 insures at all times a mixture of the same tension, irrespective of the speed of the engine, and irrespective of the richness or leanness of said mixture, as determined by the adjustment of the screw 36. That 45 is to say, even when the engine is barely turning over, or "idling", the liquid fuel for admixture with the air passing valve 4 will be just as finely atomized, or broken up into

spray, as when the engine is running at high speed and drawing in a large volume of mixture. 50

I claim,

1. In a device of the character described, an air passage constituting a mixing chamber, means for controlling the flow of air 55 through said passage, a rotating member for the segregation of successive charges of fuel proportional in volume to the flow of air through said passage, and reciprocating injecting means for projecting said charges 60 successively into said passage.

2. In a device of the character described, an air passage constituting a mixing chamber, means for controlling the flow of air 65 through said passage, a rotating member providing chambers for successive charges of fuel to be admitted to said passage, and means for varying the volume of charges admitted to said chambers in proportion to the flow of air through said passage. 70

3. In a device of the character described, an air passage constituting a mixing chamber, means for controlling the flow of air through said passage, a rotating member providing chambers for successive charges 75 of fuel to be admitted to said passage, means for varying the volume of charges admitted to said chambers in proportion to the flow of air through said passage, and reciprocating means for successively projecting the charges from said chambers into 80 said passage.

4. In a device of the character described, an air passage constituting a mixing chamber, means for controlling the flow of air 85 through said passage, a rotating member providing chambers for successive charges of liquid fuel, and means, operable by the rotation of said member, for projecting said charges under constant pressure into said 90 passage.

Dated this seventh day of October, 1914.

EDWIN G. STAUDE.
